W. F. HELMOND.
TYPEWRITING MACHINE.
APPLICATION FILED APR. 30, 1919.

1,328,626.

Patented Jan. 20, 1920.

UNITED STATES PATENT OFFICE.

WILLIAM F. HELMOND, OF HARTFORD, CONNECTICUT, ASSIGNOR TO UNDERWOOD TYPEWRITER COMPANY, OF NEW YORK, N. Y., A CORPORATION OF DELAWARE.

TYPEWRITING-MACHINE.

1,328,626.

Specification of Letters Patent. Patented Jan. 20, 1920.

Application filed April 30, 1919. Serial No. 293,837.

To all whom it may concern:

Be it known that I, WILLIAM F. HELMOND, a citizen of the United States, residing in Hartford, in the county of Hartford and State of Connecticut, have invented certain new and useful Improvements in Typewriting-Machines, of which the following is a specification.

This invention relates to the type-bar operating levers of typewriting machines, and especially to the key-lever bearings, and means for adjusting the tension of the returning springs thereof.

The invention is herein disclosed as applied to an Underwood typewriting machine in which the key-levers are journaled at the extreme rear of the machine upon a rod which extends across a comb, between the teeth of which the key-levers are set.

According to the present invention, the plate which is utilized for holding the key-levers to their bearing upon the rod may comprise an extension adapted to bear against the screws which serve to adjust the tension of the returning springs. By having this extension resilient, it may be stiff enough to serve to prevent the screws from turning under the jarring of writing or of transporting the machine, and yet at the same time may yield easily enough to enable the screws to be adjusted to vary the tension of the springs without removing the plate. This avoids the necessity of using set-screws or other devices for locking the adjusting screws.

Other features and advantages will hereinafter appear.

In the accompanying drawings,

Figure 1 is a sectional side view, largely diagrammatic, of an Underwood typewriting machine, showing the present invention as applied thereto.

Fig. 2 is a fragmentary perspective view of the comb and parts connected thereto, all but one of the key-levers removed from the comb.

Fig. 3 is a perspective view of an adjusting screw.

Fig. 4 is a perspective view of the screw-holding plate turned upside down, to show some of its features.

Fig. 5 is a bottom view of a fragment of the plate.

The key-levers 1 bear keys 2 at their forward ends, and are fulcrumed at their rear

ends 3 and are connected between their ends to the type-bars 4. The rear end 3 of each lever 1 is provided with an upwardly-opening bearing slot 5, which sets up over a horizontal transverse fulcrum rod 6. This rod extends the entire width of the system of key-levers, which work in slots 7 forming a comb in a transverse bar 8, in which said fulcrum rod is fixed. In said transverse bar are also provided screws 9 individual to the key-levers, and compression springs 10 are pressed upwardly by the screws against the key-levers for returning them to normal positions after actuation; such springs normally holding the slotted bearings of the key-levers up against the fulcrum rod.

I provide a key-lever retaining plate 11, which is mounted upon said transverse bar and extends across the machine in such position that its upper edge 12 lies just below the ends of the key-levers, to prevent the latter from being accidentally dropped from the fulcrum bar and dislodged.

This retaining plate or lock, held in place by screws 13, is made to do the further duty of locking the spring-adjusting screws 9 against accidental rotation. For this purpose, said plate 11 is extended downwardly at 14 and then bent upwardly at 15 to form a yielding retainer 16 for the screws 9, which are flat-sided and cannot turn without bending said retaining plate. Thus, by a simple and inexpensive contrivance, the key-levers are locked in position and the spring-adjusting screws 9 are prevented from accidentally rotating. The screws 9 are provided with slots 17 to receive a screw-driver, and the retainer 16 is adapted to yield easily enough to enable the screws 9 to be turned against the tension of the retainer 16.

The plate may include openings 18 in the resilient portion thereof where it joins the body of the plate; said openings serving to increase the resiliency of the extension.

Variations may be resorted to within the scope of the invention, and portions of the improvements may be used without others.

Having thus described my invention, I claim:

1. In a typewriting machine, the combination with key-levers and a rod on which they are journaled, of a plate adapted to hold said key-levers to their bearing upon the rod, a mounting for said rod, returning springs

for said key-levers held in position upon said mounting, screws adapted to bear against said springs and to be adjusted to vary the position of the springs, and an extension of 5 said plate adapted to bear against flat surfaces upon said screws to hold the screws against turning.

2. In a typewriting machine, the combination with key-levers and a rod on which they 10 are journaled, of a plate adapted to hold said key-levers to their bearing upon the rod, a mounting for said rod, returning springs for said key-levers held in position upon said mounting, screws adapted to bear against 15 said springs and to be adjusted to vary the position of the springs, and a U-shaped extension of said plate having a free edge forming a resilient member to bear against flat sides of said screws.

20 3. In a typewriting machine, the combination with key-levers and a rod on which they are journaled, of a member including a comb having teeth to space said key-levers, said rod lying against said comb, an extension of 25 said member, a spring for each key-lever lying within an opening of said member, a screw for each spring adapted to take its thrust, and threaded into said member, a plate fast to said member and having an 30 edge adapted to hold said key-levers to their bearing, and an extension of said plate adapted to bear against flat sides of said screws to hold them against accidental turning.

35 4. In a typewriting machine, the combination with key-levers and a rod on which they are journaled, of a member including a comb having teeth to space said key-levers, said rod lying against said comb, an extension of 40 said member, a spring for each key-lever lying within an opening of said member, a screw for each spring adapted to take its

thrust, and threaded into said member, a plate fast to said member and having an edge adapted to hold said key-levers to their 45 bearing, and a U-shaped extension of said plate having one free edge forming a resilient spring to bear against flat sides of said screws to hold them against accidental turning, said last-named spring adapted to yield 50 to permit the screws to turn when forcibly turned by a tool.

5. In a typewriting machine, the combination with a member including a comb, of a rod extending across said comb, a key-lever 55 lying between two teeth in said comb and having a bearing on said rod, a spring for said key-lever mounted upon said member, a screw threaded into said member and adjustable to vary the position of said spring, 60 a plate fast to said member to hold said key-lever to its bearing, and a spring extension of said plate adapted to bear against said screw to hold the screw against accidental turning and adapted to permit the screw to 65 be forcibly turned by a tool.

6. In a typewriting machine, the combination with key-levers and a rod on which they are journaled, of a plate adapted to hold said key-levers to their bearing upon the rod, a 70 mounting for said rod, returning springs for said key-levers held in position upon said mounting, screws adapted to bear against said springs and to be adjusted to vary the position of the springs, and a U-shaped extension of said plate having a free edge joined to the body of the plate along a line having openings forming a resilient member to bear against flat sides of said screws. 75

WILLIAM F. HELMOND.
